UNITED STATES PATENT OFFICE

2,505,685

TOOLHOLDER

Francis H. McClernon, Springfield, Mo.

Application January 4, 1946, Serial No. 638,968

1 Claim. (Cl. 29—49)

1

The present invention relates to lathe turrets or tool head supports and more particularly to improved means for moving and maintaining a tool head or holder in proper operating position relative to the work, and is directed to an improved construction over what is disclosed in my copending application Serial No. 525,727, filed March 9, 1944.

An important object of the invention is to provide a lathe turret or support with a longitudinally movable and rotatable tool head having means in the form of a clutch mechanism operable to maintain the tool head in a fixed position relative to the work and to rotate the tool head to present a new tool to the work. Stop means operatively associated with the clutch mechanism and the tool head serves to limit their rotary movement when moved a predetermined distance so as to present a new tool to the work.

Another object consists in associating with the tool head support, revoluble means disposed transversely of the support adjacent one end thereof and arranged when the tool head is moved to inoperative position to support the same. The revoluble means also serves to prevent the tool head from binding or sticking to the support when moved relative thereto.

A further object comprehends the provision of means for clamping the tool head support in a fixed position, and associating with the clamping means spaced adjusting screws for moving and maintaining the tool head at any desired pitch or angle so as to insure the tool being held in proper operating position relative to the work. The adjusting screws also provide means for raising or lowering the turret so that the latter may be associated with different size lathes as the particular working conditions require.

Other objects and advantages of the invention will become apparent from the following description when taken in conjunction with the accompanying claim and drawings.

Referring to the drawings in which is shown a preferred embodiment of the invention,

Figure 1 is a side elevation of the improved lathe turret mounted on a support and showing the parts in their operating position.

Figure 2 is a longitudinal, central, sectional view of Figure 1.

Figure 3 is an end view of Figure 1.

Figure 4 is a sectional view taken substantially along the lines 4—4 of Figure 1.

Figure 5 is a sectional view taken substantially along the lines 5—5 of Figure 1.

2

Figure 6 is a sectional view taken substantially along the lines 6—6 of Figure 1, and

Figure 7 is a side view similar to Figure 1 but showing the tool head and its associated parts in their inoperative position and moved away from the work.

Referring to the drawings in which like numerals indicate like parts in the several views, 10 designates a lathe turret or tool head support having a base portion 11 (Fig. 2) provided with spaced upwardly extending arms 12 and 13 which form between them a recess 14, the bottom wall 15 of which is provided with a central orifice 16, through which extends a threaded, 15 retaining bolt 17, the head 18 of which is positioned within the recess 14. The tool head support 10 may rest on a pair of spaced, parallel members 19 that are disposed transversely of the support and are carried by a lathe base or the like 20. The members 19 are provided on their inner opposed sides with aligned grooves 21 which slidably receive a plate 22, having a central threaded opening 23 that is connected to the threaded end portion of the bolt 17. The head 18 of the bolt may be provided with radial openings 24 for receiving a suitable tool so as to clamp the support 10 on the members 19 or release the support therefrom.

The arms 12 and 13 of the support are centrally formed with aligned openings 25, the walls of which constitute bearing surfaces for the axially movable operating shaft 26 that extends longitudinally through the support 10 and is connected at its forward end to the tool head or block 27, which preferably carries a plurality of space cutting or drilling tools 28 arranged selectively to be presented to the work. The tool head 27 has extended rearwardly therefrom a cylindrical reduced portion 29 that terminates in a substantially square indexing member or seat 30, that is arranged to engage the adjacent side of the support 10 when the parts are in their inoperative position (Fig. 7). The opposite end of the shaft 26 has a reduced threaded portion 31 which extends outwardly from the support 10 and receive a locking nut 32. The arm 13 of the support is formed with a recess 33 in which is positioned a coiled spring 34 that abuts at its outer end a disc or ring 35, threaded to the reduced portion of the shaft 26. The disc is formed on its outer periphery with spaced circumferentially disposed notches 36 (Fig. 3) which are arranged to equal in number the number of tools carried by the head. As shown, four 55 cutting tools 28 are carried by the head 27 and

the same number of uniformly spaced notches 36 are formed on the disc 35. The lower end of a pawl 37 is pivoted to the rear of the support 10 by a threaded bolt 38 so that its upper end may ride on the outer periphery of the disc 35 and be moved sequentially into engagement with the spaced notches 36 to prevent further turning movement in a clockwise direction of the shaft 26 but allows its free rotation in an opposite direction. The pawl 37 is yieldably maintained in engagement with the disc 35 by a spring pin 39 connected at its lower end to bolt 38 and has its upper end engaging a lug 40 on the pawl 37 (Fig. 3).

Mounted on the shaft 26 and positioned within the recess 14 are operating means referred to as a clutch mechanism which preferably comprises an engaging clutch member 41 loosely mounted on the shaft 26, and which is formed with circumferentially spaced flat projections or teeth 42 and recesses 43, which are arranged to engage and interfit with complementary formed projections 44 and recess 45 on a receiving clutch member 46, that is keyed or otherwise non-rotatably secured to the shaft 26 as at 47 (Fig. 4). The flat projections on the clutch members are preferably separated from their adjacent recesses by inclined portions 48, so as to facilitate the engagement and release of the projecting portions with their complementary recesses. Suitably connected to the engaging clutch member 41 as at 49 (Fig. 2) is an operative handle 50 that normally assumes the vertical position shown in Fig. 3 when the opposed projections on the clutch members 41 and 46 are engaged (Fig. 1) so as to co-act with the fixed adjacent side wall of the arm 13 of the support or base 10 to provide abutting means for maintaining the tool head 27 in its operative position and away from the support 10. Each of the tools 28 extends into a slot 51 (Fig. 1) in the adjacent side of the head 27 and each slot is formed on one side with an arcuate recess 52 which receives a segmental or curved plug 53, that is provided with a flat portion 54 that engages one side of the tool 28. A pair of space adjusting screws 55 extend through each side of the multiple tool head 27 to engage the adjacent tool 28 on the side opposite the plug 53.

The selective adjustment of the screws 55 act to move the tool head 28 and rotate the plug 53 in order to vary the height of the tool and maintain the same in the desired adjusted position relative to the work. As shown in Fig. 1, the work may be a cylindrical metal block 56 the outer surface of which is to be formed with external threads by one of the tools 28. The block 56 may be carried by a bracket 57 secured at 58 to the lathe base 20.

The end of the support 10 adjacent the tool head 27 has a cut out or reduced portion 59 that is provided at its opposite lower sides with outwardly spaced portions or flanges 59 preferably shaped as shown in Figure 5. The inner walls of the portions 59 have parallel grooves 60 (Fig. 6) extending the length thereof. A flat bearing plate 61 provided with reduced trunnions 62 which fit in grooves 60, is positioned within a recess 63 in the bottom 11 of the support 10 and between the portions 59. A transversely disposed roller 64 having reduced trunnions revolvably and slidably mounted in the grooves 60 above the plate 61 is positioned so as to be spaced from the arm 12 of the support (Fig. 2) and is arranged to engage and support one side of the square in-

dexing or rest member 30 when the shaft 26 and the tool head 27 are moved to their operative position toward the work 56 and away from the support, to prevent binding or sticking of the tool head when the latter is moved relative to the work, and which also reduces wear of the movable parts of the machine. When the shaft 26 and toolhead 27 are moved axially toward the support 10, the indexing member 30 is moved away and free from engagement with the roller 64 so that the parts are in their inoperative position (Fig. 7). Preferably, the corners of the indexing member 30 are reduced as at 66 to facilitate the rotation and proper positioning of the same. To accurately level and maintain the roller 64 in transverse alignment with the adjacent side of the member 30, a pair of adjusting screws 67 extend up through the bottom of the support 10 so as to engage the under side 20 of the plate 61 to raise or lower the same so as to move and maintain the roller 64 in proper contact with the adjacent side 68 of the indexing member 30 (Fig. 5).

The support 10 may be of any desired shape and size and as shown, has its bottom or base 11 (Fig. 6) of substantially triangular formation. Threaded to the base 11 and extending downwardly therefrom are a pair of front adjusting screws 69 and a rear adjusting screw 70. Each of these three screws has an integral nut or tool engaging head 71 and a downwardly projecting tapered portion 72 that bears against a plate 73 mounted on the top of the supporting members 19. The plate 73 has a central opening through which loosely extends the retaining bolt 47. It will be seen that when the parts are assembled and the bolt 47 tighten-up on the plate 22, the tool head support 10 will be firmly clamped in position. Should it be necessary to tilt the support to any desired angle so as to insure one of the tools 28 carried by the head 27 being moved and maintained in proper position relative to the work, this vernier adjustment can be accomplished by selectively adjusting the screws 69 and 70 to raise or lower the same which in turn moves the support 10 and its associated parts in the desired direction.

The tool head support 10 may be enclosed in a removable curved cover or hood 75 that has a depending flange or front portion 76 and a transverse slot 77 in the top thereof through which extends the operating handle 59 of the clutch mechanism. The sides of the hood overlap the support 10 and may be detachably secured thereto by the screws 78. The hood 75 prevents foreign matter from entering the clutch mechanism and other movable parts carried by the support and which might interfere with the efficient operation of the device.

When the tool head 27 and its associated parts are moved to operative position relative to the work, the projections 41 and 46 of the clutch mechanism are in engagement (Fig. 1) and the operating handle 59 is in its vertical position as shown in Figure 3. The indexing member 30 on the tool head is now moved away from the support 10 and engages at its lower side 68 the roller 64. When it is required to move the multiple tool head 27 away from the work, the handle 59 is first rotated in a clockwise direction to the position B (Fig. 3) which causes the projections 42 on the clutch engaging member to interfit with the complementary recesses 45 on the clutch receiving member 46. The tension of the spring 34 is now released and moves the shaft 26 and tool

head 27 away from the work and toward the support so that the indexing member 30 is free from engagement with the roller 64 and the parts assume the position as shown in Fig. 7. The clutch members 41 and 46 are now interlocked and rotation of the handle 50 in a counter-clockwise direction to position A (Fig. 3) will rotate the shaft 26 and multiple tool head 27. At the same time, the pawl 37 rides on the outer periphery of the disc 35 until it falls into one of the notches 36 that tends to arrest its further rotary movement in order to present a new tool to the work. The handle 50 is then moved in a counter-clockwise direction to its vertical position which releases the projections on the clutch engaging member from the recesses on the clutch receiving member and returns the projections on the clutch members into engagement (Fig. 1), thus imparting forward axial movement to the shaft 26 and tool head so as to again move the latter in operative position relative to the work. The movement of the clutch engaging member 41 relative to the clutch receiving member 46 is facilitated by the inclined portions 48 of these members. The operating handle 50 may be either manually operated or connected to automatic means for causing its operation. The operation of the clutch mechanism to move and maintain the tool head in position relative to the work may be repeated and different types of tools presented to the work.

When the operating handle 50 and its associated parts are moved to the position A (Fig. 3) the projections on the clutch members are moved into the recesses on the complementary members so that manual pressure applied to the outer end of shaft 26 and the nut 32 will move the slide shaft 26 and tool head 27 towards the work without disturbing the rotary position of the tool 28 that is in operative alignment with the work. This is an important and convenient feature since in cutting a thread with an ordinary tool holder as used on most lathes, the operator makes a cut and then moves the micrometer feed back and returns the carriage to the starting point, resets the micrometer feed and makes another cut. Sometimes the operator forgets the number he is working with on his micrometer feed and either moves it up too much or not enough. This either damages the work or loses valuable time. In the present invention, on the other hand, the parts are constructed and arranged so that if the operator is making a cut, he sets his micrometer on the lathe, makes a cut but instead of moving the micrometer feed back, he merely moves the operating handle 50 from its vertical position (Fig. 5) to the position A (Fig. 5). This causes the tool head 27 to be moved away from the work but does not disturb the operative position of the cutting tool 28. The tool head 27 may now be reset and the tool locked in a fixed position merely by the operator pushing against the back of the shaft 26 with the heel or palm of his hand and then returning the operating handle 50 to its vertical position which causes the projecting portions of the clutch mechanism to be moved into engagement so as to maintain the tool head in operative position relative to the work. The micrometer feed is then moved to the desired amount and the cuts or threads on the work are made uniform.

The clamping connection of the tool head support 10 and its associated parts to the spaced members 19 provides means for raising or lowering the support 10 to properly position the

tool head relative to the work and also allows the tool head support 10 to be conveniently attached to different size lathes. The selective vernier adjustment of the support 10 through the three screws 69 and 70 insures the multiple tool head holder 27 and the tools 28 being tilted at the proper angle to properly contact the work. Additionally, the adjustment of each of the tools 28 by the segmental plug 53 and its coacting screws 55 provides simple and efficient means for varying the height of each of the tools 28 as working conditions may require.

The engagement of the lower side of the square indexing member 30 with the roller 64 when the tool head 27 is moved away from the support 10 so as to present the tools 28 in operative position relative to the work, insures the free axial movement of the tool head and its associated parts without danger of sticking or without being subjected to unnecessary wear.

It is to be understood that the form of the invention shown and described is merely illustrative of a preferred embodiment and that such changes may be made as fall within the purview of one skilled in the art without departing from the spirit of the invention and the scope of the claim.

I claim:

30 A tool comprising a support having spaced upwardly extending arms, said arms having aligned openings, a shaft mounted in said openings for rotational and axial movements and extending beyond said arms, a tool head secured to one end of said shaft, coacting stop means mounted on the opposite end of said shaft and the support to releasably maintain the shaft in a predetermined rotary position, spring means encircling said shaft and located between said stop means and one of said arms to normally 35 move the tool head toward the second arm, operating means located between said arms including an engaging member mounted for rotation on said shaft and a receiving member fixed to said shaft, the inner wall of said first named 40 arm constituting a reaction abutment for said engaging member, said members having opposed projections and recesses provided with cooperating inclined portions whereby rotation of said engaging member to align the projections axially 45 moves the shaft against the action of the spring to advance the tool head toward the work and away from the adjacent arm, the projections having flat cooperating surfaces to maintain the tool head in the advanced position, means for rotating 50 said engaging member, said tool head having a regular polygonal portion in the rear thereof, a roller adjustably mounted on said support in advance of said second arm to engage and support a side of said polygonal portion when the 55 tool head is moved to the advanced position.

FRANCIS H. McCLENNON.
